(57) **CLAIM**

The ornamental design for a wall base with curved profile, as shown and described.

DESCRIPTION

FIG. 1 is a perspective view of a wall base with curved profile showing my new design;

FIG. 2 is a top plan view thereof;

FIG. 3 is a front elevation view thereof;

FIG. 4 is a right elevation view thereof;

FIG. 5 is a left elevation view thereof;

FIG. 6 is a rear elevation view thereof; and,

FIG. 7 is a bottom plan view thereof.

The wall base with curved profile is shown with a symbolic break in its length. The appearance of any portion of the wall base with curved profile between the break lines forms no part of the claimed design.
